DESIGN FOR A DISPLAY FIGURE OR SIMILAR ARTICLE

Elsa Maria Kafka, New York, N. Y.

Application January 31, 1942, Serial No. 105,540

Term of patent 3½ years

To all whom it may concern:

Be it known that I, Elsa Maria Kafka, a citizen of former Austria, residing at New York, in the county of New York and State of New York, have invented a new, original, and ornamental Design for a Display Figure or Similar Article, of which the following is a specification, reference being had to the accompanying drawing, forming part thereof.

In the drawing:

Fig. 1 is a top perspective view of a display figure or similar article, showing my new design; and

Fig. 2 is a bottom perspective view thereof.

I claim:

The ornamental design for a display figure or similar article, as shown.

ELSA MARIA KAFKA.
